(57) **CLAIM**

The ornamental design for a necklace with pendant, as shown and described.

DESCRIPTION

FIG. 1 is a front view of a necklace with pendant of my new design;

FIG. 2 is a rear view thereof;

FIG. 3 is a right side perspective view thereof;

FIG. 4 is a left side perspective view thereof;

FIG. 5 is a top front perspective view thereof;

FIG. 6 is a bottom front perspective view thereof;

FIG. 7 is a front right perspective view thereof;

FIG. 8 is a rear left perspective view thereof;

FIG. 9 is an enlarged front view of a central element of the necklace with pendant shown in FIG. 1;

FIG. 10 is an enlarged front view of upper central elements of the necklace with pendant shown in FIG. 1; and,

FIG. 11 is an enlarged front right perspective view of the central element of the necklace with pendant shown in FIG. 7.

The dot-dash broken lines represent the designation of enlargement views and form no part of the claimed design.
